UNITED STATES PATENT OFFICE

ROBERT JOHN ALEXANDER CHANDLER, OF LONDON, ENGLAND, ASSIGNOR TO AMERICAN MACHINE & FOUNDRY COMPANY, A CORPORATION OF NEW JERSEY

CUT-OFF FOR CIGARETTE MACHINES

Application filed September 18, 1929. Serial No. 393,463.

This invention relates to cutoffs for cigarette machines, particularly cutoffs designed to be relatively vibrationless when used at high speeds.

5 Among the objects of the invention are to produce a cutoff in which the moving parts not completely balanced are of relatively little weight, and in which smooth rotary or harmonic motion takes the place of reciprocation, and to accompany these advantages with 10 simplicity and cheapness of construction. To this end the cutting blade is supported for pivotal and rotary motion on two pivots which are given differential motion such that 15 the cutoff blade has very rapid yet smooth motion across the path of the cigarette rod.

With these and other objects in view, the invention consists in certain constructions and combinations which will be hereinafter 20 fully set forth and then particularly pointed out in the appended claims.

In the accompanying drawings in which like characters of reference indicate the same or like parts:

25 Fig. 1 is a front elevation of a cigarette rod cut-off machine constructed in accordance with the invention; and

Fig. 2 is a side elevation of the machine shown in Fig. 1.

30 In carrying the invention into effect there is provided in combination with a cigarette rod guide, a cutting element, spaced pivots on which said cutting element is supported, and means for imparting differential orbital movement to said pivots to produce movement of said element across the cigarette rod. In the best constructions, these pivots are mounted for movement about a common center, and preferably said means operates to 35 revolve said pivots in opposite directions about said center. In the best constructions, said means is timed to cause maximum speed of movement near cutting position.

40 The various means referred to may be widely varied in construction within the scope of the claims, for the particular device selected to illustrate the invention is but one of many possible embodiments of the same. The 45 invention, therefore, is not to be restricted to

the precise details of the structure shown and described.

Referring to the drawings, orbital movement is imparted to one of the pivots or crank pins 2 on which the cutting element is carried, 55 by a disk 3 to the face of which the pin is secured, which disk is fastened to a shaft 4 journaled in a bearing frame 5 on a table 6 forming part of the frame of the cigarette machine of which this cutoff forms a part. 60 This disk is driven by a bevel gear 8 on the shaft 9 driven through gear 10 from the main drive of the cigarette machine.

The crank pin 16 on which the lever 17 is pivoted at its mid-portion is revolved in a 65 concentric path of greater radius about that of the pin 2 but in reverse direction by a disk 14 mounted on sleeve 13 in a bushing 11 in an arm 12 of the bearing frame 5, and driven by a stationary gear 15 meshing with the gear 8. 70 The lever 17 is provided with a slot 20 embracing the pin 2, the latter being provided with a roller 19 to reduce friction.

The cutoff element consists of this light 75 lever 17, having fastened to its outer end a narrow cutoff blade 18. Preferably this blade is slightly inclined to the plane of disk 14 so as to compensate for the travel of the rod while the blade is passing through it, and this insures a cut which is exactly square. 80 The present device, however, is designed to reduce this travel to a minimum through making the blade very narrow and passing the blades through the rod at high speed made possible by the absence of vibration and 85 by the additional impetus given the blade at cutting position by the relative movement of the two pivots.

In cutting the cigarette rod, the cutoff 90 blades cooperate in the usual manner with suitable stationary guide and ledger tubes 21, 22 and 23. Suitable grinding disks 25 and 26 engage the blade between cuts.

As shown in Fig. 1, the driving gears of the 95 disks 3 and 14 are so timed that the pins 2 and 16 pass each other traveling in opposite directions when approximately in alignment with their common center and the cigarette rod. As a result, the blade 18 is given in addition to its circular movement with the disk 100

14, a quick forward movement as it approaches cutting position. Thus with the disks and driving gears operating at moderate speed, the blade near cutting position will travel at a maximum annular speed much greater than that of any of its heavy driving parts. In the construction shown, the speed of travel of the blade is enhanced by the fact that the pins 2 and 16 are traveling in opposite directions and because the distance from the fulcrum point at pin 16 to the blade is several times that to the pin 2, when the blade is near cutting position.

It should be noted that by the foregoing construction reciprocating parts are eliminated and that the only parts having other than purely circular motion and very high speed are light in weight and have an annular harmonic motion which is slowest where a change of direction occurs, thereby insuring freedom from vibration.

What is claimed is:

1. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod.

2. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod, said element comprising a lever mounted on said pivots and a cutoff blade at the end of said lever.

3. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod, said element including a narrow cutoff blade.

4. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod, said element having a sliding connection with one of said pivots.

5. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod, said element having a radial slot with one of said pivots engaging said slot.

6. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod, said pivots comprising two radially spaced crank pins.

7. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod, said pivots being mounted for revolution about a common center.

8. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod, said pivots comprising crank pins, and rotating disks carrying said crank pins.

9. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod, said means operating to revolve said pivots in opposite directions.

10. In a cigarette rod cutoff mechanism, the combination with a cigarette rod cutting element, of spaced pivots on which said cutting element is mounted, and means for imparting different orbital movements to said pivots to produce rapid movement of said element across the path of the cigarette rod, said means being timed to cause maximum speed of movement of said element near rod cutting position.

11. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod, said means operating to revolve said pivots in concentric paths of unequal radii, and a slot at one end of said element embracing the pivot having the least radius of revolution.

12. In a cigarette rod cutoff mechanism, the combination with a cigarette rod cutting element, of spaced pivots on which said cutting element is mounted, and means for imparting differential orbital movements to said pivots to produce rapid movement of said element across the path of the cigarette rod,

said means operating to revolve said pivots in concentric paths, and operating connections timed to cause said pivots to pass each other approximately between their common center and the cigarette rod.

5 In testimony whereof, I have signed my name to this specification.

ROBERT JOHN ALEXANDER CHANDLER.
